Patented June 10, 1919.

FIG. 1.

FIG. 2.

E. A. Inventor
GORSETH.

By *E. A. GORSETH*

Attorney

UNITED STATES PATENT OFFICE.

EREK A. GORSETH, OF WALL, SOUTH DAKOTA.

CALF-WEANER.

1,306,590.

Specification of Letters Patent. Patented June 10, 1919.

Application filed October 24, 1918. Serial No. 259,525.

To all whom it may concern:

Be it known that I, EREK A. GORSETH, a citizen of the United States, residing at Wall, in the county of Pennington and State 5 of South Dakota, have invented certain new and useful Improvements in Calf-Weaners; and I do hereby declare the following to be a full, clear, and exact description of the invention, such as will enable others skilled 10 in the art to which it appertains to make and use the same.

This invention relates to calf weaners, and more particularly to a device which is specially adapted to be attached to the muzzle 15 of a calf so as to permit it to graze while effectually preventing suckling of the cow.

One of the main objects of the invention is to provide a weaner of simple construction and operation which may be produced at 20 very small cost and may be readily applied.

A further object is to provide a weaner provided with a plurality of sharpened elements or points which will act in the well known manner to stick the mother cow so 25 as to cause her to move away from the calf in the event that the calf attempts to suckle her.

Further objects will appear from the detailed description.

30 In the drawing:

Figure 1 is a perspective front view of a weaner constructed in accordance with my invention.

Fig. 2 is a similar view of a modified 35 form.

In the form illustrated in Fig. 1, a piece of wire of suitable gage is bent to provide a substantially rectangular supporting frame 1, the end portions of the upper arm 40 1^a of which are bent to provide opposed outwardly directed intermediate V-shaped elements 2 at the upper ends of which are formed the inwardly directed U-members 3, the upper arms of which are extended and 45 pointed to provide the points or spurs 4. As will be noted, the inner ends of the members 3 are spaced a short distance apart to provide an opening 5 for receiving the central partition member of cartilage of the 50 calf's nose between members 3. When the frame has been placed in such position as to bring the cartilage partition of the calf's nose between members 3, these members may be forced toward each other by means of a 55 loop of wire 6 secured through the loops 7 formed at the inner ends of the upper arms

1^a of frame 1, this wire 6 being twisted so as to force members 3 into tight engagement with the cartilage wall or partition member above the lower thickened portion thereof, 60 thus tightly securing the frame in position. When the frame is thus secured, it will swing outwardly away from the calf's muzzle so as to permit it to graze, when the calf's head is lowered, in the well known manner. 65

Main frame 1 is provided, adjacent each end, with a transverse reinforcing member 8 formed from a single piece of wire, this member being wrapped about the lower bar 1^b of the frame, as at 9, and bent 70 at right angles and sharpened to provide a forwardly projecting spur 10. The upper portion of member 8 is looped over spur 4 so as to provide a substantially U-shaped reinforcing and guiding member 75 11, therefor, the forward arm 11^a of this member being extended downwardly and wrapped about top arm 1^a of the frame, as at 12, and then bent at right angles and sharpened to provide a forwardly projecting spur 13 in substantially vertical alignment with spur 10. A reinforcing member 14, which is formed from a single length of wire, is provided at the transverse center of main frame 1, and is wrapped about each 80 end bar 1^b thereof, as at 15, this member being extended beyond the end bar of the frame and sharpened to provide laterally projecting spurs 16, these spurs being substantially in the plane of spurs 4. The 85 members 8 and 14 thus serve to effectually brace the main frame 1 against bending or distortion while also providing pointed elements or spurs which project both forwardly and laterally of this main frame so as to 90 act to the best advantage for the purpose specified. As this device may be readily formed by bending from wire of suitable gage and temper, it may be produced at very 95 low cost and is therefore very practical. 100 Also, the frame being formed of wire is relatively light but, due to the particular relation between this frame and the bracing members, it is held rigidly in shape.

The form illustrated in Fig. 2 is very 105 similar to that shown in Fig. 1, the principal distinction being that the reinforcing members 8^a which are substituted for members 8 are not extended and passed about the spurs 4 so as to form bracing and guide 110 members therefor, but are wrapped directly about the upper bars 1^a of the main frame

1, as at 12^a. In all other respects, this form is similar to that illustrated in Fig. 1 and may be constructed and applied in the same manner.

5 What I claim is:

1. In a calf weaner, a main frame formed from a continuous piece of material, said main frame being provided above the body thereof with opposed gripping elements and 10 laterally projecting spurs carried thereby, and reinforcing members extending transversely of the main frame and secured to the upper and lower bars thereof, the end portions of said members being bent substantially at right angles and sharpened to provide forwardly projecting spurs.
2. In a calf weaner, a main supporting frame of substantially rectangular shape having end portions of its upper bars bent to 20 provide opposed gripping members for engagement with the central web of a calf's nose so as to secure the frame thereto, and bracing members extending transversely of the frame and wrapped about the upper and 25 lower bars thereof so as to secure the same against relative movement, the end portions of said bracing members being bent substantially at right angles and sharpened to provide forwardly projecting spurs.
3. In a calf weaner, a substantially rectangular main frame having the end portions of its upper arm bent to provide opposed gripping members for engagement about the central web of a calf's nose, said 35 gripping members being provided with integral elements extending laterally above the main frame, and bracing members extending transversely of the main frame, said bracing members being secured to the lower 40 bar of the main frame and provided with forwardly projecting spurs, the upper portions of the bracing members being looped

over the said laterally projecting elements of the securing members so as to form substantially U-shaped brace and guide members 45 therefor and then secured to the upper bars of the main frame.

4. In a calf weaner, a main frame formed from a continuous piece of wire bent to provide a substantially rectangular frame, the 50 end portions of the upper arm of this frame being bent to provide opposed inwardly directed substantially U-shaped members the upper arms of which are extended to form laterally projecting spurs, and brace members extending transversely of the frame and secured to the upper and lower bars thereof, said brace members being looped over the spurs of the opposed U-shaped gripping members so as to guide and brace the same 60 and being provided with forwardly projecting spurs.

5. In a calf weaner, a substantially rectangular main frame formed from a continuous piece of wire bent to provide a rectangular body portion the end portions of the upper arms of which are bent to provide upper and lower inwardly directed substantially U-members and intermediate outwardly directed substantially V-shaped 70 members connecting the U-members, the upper arms of the upper U-members being extended to form laterally projecting spurs, and brace members extending transversely of the frame and secured to the upper and 75 lower bars thereof, said brace members being looped over said spurs so as to provide brace and guide members therefor.

In testimony whereof I affix my signature in presence of two witnesses.

ERIK A. GORSETH.
